(57) **CLAIM**

The ornamental design for a mouthpiece part of electronic cigarette, as shown and described.

DESCRIPTION

FIG. 1 is a top, front and left side perspective view of a mouthpiece part of an electronic cigarette showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a bottom and right side perspective view of the mouthpiece part and a power part of an electronic cigarette released away; and,

FIG. 9 is a bottom and right side perspective view of the mouthpiece part and the power part of the electronic cigarette assembled together.

The broken line illustration of the power part of the electronic cigarette in FIGS. 8 and 9 forms no part of the claimed design.
